ATTORNEY

UNITED STATES PATENT OFFICE

133,793

DESIGN FOR A NEGLIGEE

Estelle Appel, New York, N. Y.

Application August 13, 1942, Serial No. 107,926

Term of patent 3½ years

To all whom it may concern:

Be it known that I, Estelle Appel, a citizen of the United States of America, residing in New York city, county of New York, and State of New York, have invented a new, original, and ornamental Design for a Negligee, of which the following is a specification, reference being had to the accompanying drawing, forming part thereof, wherein:

I claim:

The ornamental design for a negligee, substantially as shown.

ESTELLE APPEL.
